His Attorney.

UNITED STATES PATENT OFFICE

1,944,740

COMBINED AUTOMATIC AND MANUAL
CIRCUIT-CONTROL DEVICES

Leonard P. Hutt, Schenectady, N. Y., assignor
to General Electric Company, a corporation
of New York

Original application February 28, 1930, Serial
No. 432,204. Divided and this application
August 5, 1932. Serial No. 627,590

7 Claims. (Cl. 62—4)

My invention relates to circuit controlling devices, particularly circuit-controlling devices for controlling electrically operated apparatus, such as domestic electric refrigerators or the like.

5 This application is a division of my copending application, Serial No. 432,204, filed February 28, 1930, and assigned to the same assignee as the present invention.

In refrigerator controlling devices of the character set forth, in order to avoid a prolonged shutdown of the refrigerator in case of some slight failure of the control device, it is desirable that it be capable of being quickly replaced by another unit.

15 It is also desirable that such replacement be made without the necessity of taking apart any of the control mechanism or of disconnecting and reconnecting wires with the possibility of making wrong connections in putting in a new control device. Appearance and safety require that any means for instantly connecting the control device to render it operative be concealed and at the same time permit quick replacement. An arrangement having these desirable features will 25 not only save time but will insure proper operation of the apparatus controlled after a new unit has been put in to replace the defective unit.

Hence, it is a general object of my invention to provide an improved refrigerator control having 30 the advantageous features noted above.

More specifically, it is an object of my invention to provide a sub-panel connection means permitting said control device to be quickly removed from and connected to the sub-panel to 35 control the refrigerator circuit, said connection permitting the device to be quickly replaced by a new control device in case of failure.

It is a further object of my invention to provide a connection means for the control device 40 which will eliminate the necessity of disconnecting and reconnecting the wires to the control or the connecting means.

Another object of my invention is to provide a connecting means which is concealed for the sake 45 of appearance and safety and in which nevertheless quick replacement of a defective unit by a new unit is possible.

Other objects will appear hereinafter.

In the preferred embodiment of my invention 50 I provide an automatic switch means responsive to different predetermined temperatures. It consists of an overcenter snap switch operated by means of a temperature-responsive device. A resilient means under compression opposes the 55 temperature-responsive device and the compres-

sion of this resilient means may be varied to change the temperatures to which the switch will respond. A member biased to open the switch is normally held against its bias by means of a heat responsive device which responds to over-load conditions to release the biased member to open the switch. A manual control means is provided for releasing the biased member from the control of the heat responsive device and for placing the biased member under the control of the heat responsive device thus manually controlling the switch. The switch mechanism is provided with a cover through which the adjusting means for the resilient means opposing the temperature responsive device and the means for releasing the biased member from the control of the heat responsive device extend.

In order to permit the refrigerator controlling device to be readily replaced in case of failure, a sub-panel is mounted on the refrigerator with 75 electrical connecting means provided thereon whereby when the controlling device is placed on the sub-panel, the proper electrical circuits will be established to permit control of the refrigerating apparatus by the controlling device. By 80 sealing the cover on the controlling device tampering by unauthorized individuals is prevented.

In the drawing, Fig. 1 represents an exploded view of the cover, switch mechanism, and sub-panel to show their relation and cooperation; Fig. 85 2 is a plan view of the switch mechanism; Fig. 3 is a section of the switch mechanism and sub-panel; Fig. 4 shows the switch mechanism mounted upon a refrigerator; Fig. 5 shows the refrigerator circuit.

90 Referring to Fig. 2, the stationary contact 10 of the switch mechanism and the movable contact 11 cooperate to open and close a circuit through the refrigerator motor in response to the temperature-responsive device 26. The elements 12 and 13 mechanically connecting the member carrying the movable contact and lever 14, are the pivoted means and spring means for causing the snap action of the movable contact 11. Urging the switch mechanism to the open 95 position is the resilient means 15 in contact with lever 14 and under compression. This resilient means determines the temperatures at which the switch is opened and closed. In contact with the other end of the resilient means is a lever 16 105 which is pivotally mounted at the point 17. A screw 18 is supported in a bracket 18' and may be adjusted by means of the dial knob 19 to move the lever mechanism 16 about its pivot to vary the compression of spring 15. This results 110

in varying the temperatures to which the switch mechanism responds. A stop 19' is provided for the dial knob 19.

It will be noted that by turning the knob 19 5 in a counter-clockwise direction to release the screw 18 from the lever 16, the knob and screw may be withdrawn. This permits the lever 16 to be removed from its pivot 17, and the spring 15 then drops out. This permits ready assembly 10 of the compression spring and its adjusting means, a factor of great importance in the manufacture of the device.

Referring to Figs. 2 and 5, in series with the switch mechanism is the resistor 20₁ which upon 15 overload conditions heats up. The refrigerator motor control circuit shown in Fig. 5 is set forth and claimed in my copending application, Serial No. 448,731, filed April 30, 1930. This causes the heat responsive element 20 to assume a 20 curved shape to the right and release the pivoted member 21. Member 21 is urged about its pivot 21' in a counter-clockwise direction by its spring biasing member 21₁ to open the switch mechanism and lock it in the open position. The pivoted member 21 has attached thereto an element 24' which carries thereon designations to show 25 when the switch is off and on. These designations appear through a slot 8' of the cover 8 which is provided for the controlling device.

30 A member 22 rotatably mounted and provided with the extension 23 and the adjusting handle 25 cooperates with the heat responsive element 20 of bimetallic material and the pivoted member 21. By rotating the member 22 in a clockwise direction, the extension 23 moves the heat responsive element to the right, thereby releasing the pivoted member 21 to open the switch. Upon reversing the direction of rotation of the member 22, the reset finger or extension 23 35 will contact with the inclined surface 24 of the element 21 to rotate this element 21 in a clockwise direction, permitting the heat responsive element 20 to move to the left and again lock the pivoted member 21 against its spring bias 21₁. 40 A stop member 23₁ is provided on member 22 to limit rotation of member 22 in a clockwise direction to prevent damage to the heat responsive element 20.

The temperature-responsive device 26 is of 50 the well known sylphon bellows type. The pipe 27 extends into the refrigerating compartment, and the fluid within the sylphon bellows expands and contracts in response to the temperature changes within the compartment, causing 55 the bellows to expand and contract in response thereto to actuate the switch mechanism.

In Figs. 2 and 3, are shown the contact elements 40 and 41 which are mounted in the base 9 and cooperate with a plug (not shown) connected to the power lines. These contact elements are electrically connected to the apparatus mounted on the base 9 as shown in Fig. 5.

It is understood of course that the refrigerator motor M with its running winding R and 60 starting winding S and the connections for the same are mounted in the refrigerator and are connected to the resilient contact members 32, 33 and 35 on the sub-panel 37 by means of conductors as shown at 36 in Fig. 1 and Fig. 5, the 65 sub-panel 37 being mounted on the refrigerator. Resilient member 34 is connected to apparatus within the refrigerator of no interest to my present invention and does not affect the 70 operation of my device. Rigid contact members 75 such as 33', shown in Fig. 3, serve to make the

necessary connections between the resilient contact members on the sub-panel and the apparatus carried by the base 9. The electrical connections between these contact members 33 and the apparatus carried on base 9 is shown in Fig. 5.

For the purposes of this application it is not necessary to go into the discussion of the circuit any further than to show how the connections are made. The theory and operation of the circuit is set forth and the particular apparatus claimed in my copending applications, identified above.

Briefly, the coils 28 and 28' cooperate to open the contact 29₁ upon establishing running speed of the motor M to take the starting winding off the line. The resistor 30 is a limiting resistor for starting the motor and the heating resistor 20₁ is for the purpose of tripping the switch in case of overload by causing the bimetallic strip 20 to bend outwardly and release the biased member 21 to open the switch, thus taking the motor M off the lines.

To remove the control switch from its base, 100 the sylphon tube 27 must be straightened within the refrigerator, it having been bent to fit the interior thereof, and four screws (not shown) which hold the base 9 over the sub-panel must be unscrewed. The base then lifts off with the sylphon tube as a unit, thus making it an easy 105 task to replace it with a new unit and fastening the new unit to the sub-panel.

To be made operative, the switch mechanism carried by the base 9 is placed over the sub-panel 37 and screwed thereon, the sylphon tube 27 extending into the refrigerator and being properly adjusted.

The rigid extensions 33' extending through the base 9 contact with the resilient members 115 33 thus placing the coil 28 in parallel with the starting winding S and the coil 28' in series with the running winding R and the thermostatic switch as shown in Fig. 5.

In operation the contacts 10 and 11 are closed 120 and opened with a snap action in response to the expansion and contraction of the sylphon bellows 26. As the sylphon bellows expands in response to a rise in temperature in the refrigerator, the force of the spring member 15 is gradually overcome to move the pivoted member 14 to the left. This motion is transmitted to the pivoted member 12 and carries its pivoted end to the left until the spring 13 and member 12 are parallel. At this point the tension in the spring is 130 greatest. As the pivoted end of the member 12 continues to move to the left, a position of unbalance results and the spring in assuming a position of least tension causes the member carrying the contact 11 to close on the contact 10 135 with a snap action.

As shown in Fig. 5, this completes a starting circuit through the windings of the motor M to start the motor. As the refrigerator is cooled, the sylphon bellows contracts and the switch is 140 opened to stop the motor in the reverse manner set forth above.

As pointed out, the compression of the resilient member 15 may be varied by turning the dial knob 19. Rotating the lever 16 in a clockwise direction increases the compression in the spring 15. It will be noted that the spring 15 opposes the action of the sylphon bellows 26. Increase in the compression of the resilient member 15 raises both the opening and closing temperatures 150

of the switch mechanism since with a greater compression in the resilient member 15, a higher temperature is needed to cause the greater pressure in the sylphon bellows 26 necessary to overcome the compression in the spring member 15.

5 A screw means 11' is provided for rotating the member carrying the contact 11 about its pivot 21'. Moving the contact 11 to the right has the effect of decreasing the temperature necessary to close the switch mechanism, since it will then be necessary for the pivoted end of the element 12 to move a shorter distance to trip the switch than before the adjustment was made. Likewise, when the pivoted member 11 is permitted to rotate in a counter-clockwise direction to move the contact further to the left when the screw means 11' is moved to the left, the pivoted element 12 must move a greater distance before the switch mechanism is closed, thereby increasing the temperature necessary to close the switch mechanism. The shape of the lever mechanism 16 is for the purpose of permitting the adjusting means to be mounted at the end of the switch and to make room for the resistor 30.

25 It will be noted that by the special construction of the lever 16 for compressing the spring 15, the adjusting knob may be mounted on the side as shown. The shape of the lever provides space for the resistor 30, thus decreasing the 30 space necessary for the apparatus. By making the member 22 perform two functions the number of parts is reduced, thus reducing the space necessary to mount the parts permitting a smaller control device unit. The result is a very compact unit with the controls all on the same side of the device and with fewer adjusting members.

35 It will thus be seen that I have provided numerous improvements in my automatic switch mechanism including the means for making the various adjustments thereon and for providing the necessary electrical connections thereto.

The embodiment of the invention illustrated and described herein has been selected for the 45 purpose of clearly setting forth the principles involved. It will be apparent, however, that the invention is susceptible of being modified to meet the different conditions encountered in its use, and I, therefore, aim to cover by the appended 50 claims all modifications within the true spirit and scope of my invention.

What I claim as new and desire to secure by Letters Patent of the United States is:

1. In combination, an electric refrigerator control device including a base, a motor controlling switch mechanism mounted on said base responsive to predetermined temperature and overload conditions to control a refrigerator motor, a motor controlling resistor mounted on said base responsive to overload conditions, motor controlling electro-responsive means on said base, said switch mechanism, resistor and electro-responsive means being electrically interconnected to provide a controlling circuit for a refrigerator motor, rigid 65 contacts extending through said base and electrically connected to said resistor, switch mechanism, and electro-responsive means, an independently mounted sub-panel carrying thereon resilient motor circuit contact members electrically connected to the refrigerator motor, said rigid contacts and resilient contact members being arranged in cooperating spaced relation to provide quick detachable electrical connections for said control device.

75 2. A detachable electric refrigerator control

device for a motor, comprising a base, a switch responsive to predetermined conditions for opening and closing a circuit through said motor, a resistor mounted on said base responsive to overload conditions of said motor, a relay mechanism 80 on said base for changing the electrical connections to said motor, said switch, relay and resistor being electrically connected, rigid contact members extending through said base and electrically connected to said switch, resistor and relay, a sub-panel independently mounted provided with resilient contact members cooperating with said rigid contact members to provide quick detachable electrical connections for said control device, and electrical conductors for connecting said resilient members to the refrigerator motor.

3. A detachable control device for an electric motor-driven refrigerating apparatus, having a hollow base, a plurality of motor control members mounted on the top of said base and electrically connected to provide a control circuit for the motor, contact members extending through said base into the hollow part thereof and electrically connected to said motor control members, a sub-panel connected to the motor and independently mounted and provided with contact members for cooperating with said contact members on said base to provide quick detachable electrical connections for said control device, said hollow base enclosing said sub-panel when said contact members are 105 in contact with each other, said sub-panel permitting instant replacement of said control device by another control device.

4. A detachable control device for an electric motor driven refrigerating apparatus comprising 110 a hollow base, a plurality of control members mounted on said base and electrically connected to provide a control circuit for the motor, contact members extending from the side of said base for connecting to a power supply, other contact members extending through said base into the hollow portion thereof, electrical connections to said first contact members and to said control members, a sub-panel independently mounted and provided with contact members connected to the 120 motor for cooperating with said contact members extending through said base to provide quick detachable electrical connections for said control device, said sub-panel fitting into the hollow of said base when said base is in operating position with 125 the contact members in engagement, said electrical connections providing a circuit from said power supply contacts to said sub-panel contact members when said sub-panel contact members and said contact members on said base are in engagement.

5. An apparatus provided with a chamber having an electric motor therein, a sub-panel permanently mounted on said apparatus and provided with a plurality of contact-making members, said contact-making members being provided with terminals, electrical conductors for connecting said motor and said contact members, a detachable control device comprising a hollow base, a plurality of motor-control elements mounted on said base and electrically inter-connected, contact members extending through said base into the hollow part thereof and connected with said motor-control elements, said sub-panel contact members and said contact members on said base being 135 in contact with each other to provide an electrical controlling circuit between said motor-control elements and said motor when said control device is placed in operating position with said contact members in engagement, said hollow base en- 140 145 150

closing said sub-panel when said control device is in operating position whereby said contact members are concealed and protected from accidental contact.

- 5 6. In combination, a refrigerator having an electric motor therein for operating the same, a sub-panel on said refrigerator, contact members individually mounted on said sub-panel and provided with terminals on said sub-panel, electrical conductors extending from said motor and connected to the terminals of said contact members, a detachable control device including a hollow base and provided with contact members extending from the side of said base into the hollow
- 10 15 part thereof for connecting to a power supply, automatic switch means and motor starting means provided with an overload device mounted on said base, said power supply contact members, switch, starting device, and overload device being electrically connected, contact members connected to said switch, starting device and overload device and extending through the base into the hollow part thereof for cooperating with said resilient contact members when said base is in
- 15 20 25

operating position for providing an electrical control circuit for said motor, said base when in operating position completely enclosing said sub-panel whereby access thereto can only be had by removing said control device, said control device being instantly replaceable by another control device.

7. In combination, an electric refrigerator motor control device including a base, a motor controlling switch mechanism mounted on said base, a motor controlling resistor mounted on said base, a motor controlling electroresponsive means on said base, said switch mechanism, resistor and electroresponsive means being electrically interconnected and rigid contacts extending through said base and electrically connected to said resistor, switch mechanism, and electroresponsive means, an independently mounted sub-panel carrying thereon resilient motor circuit contact members, said rigid contacts and resilient contact members being arranged in cooperating spaced relation to provide quick detachable electrical connections for said control device.
